UNITED STATES PATENT OFFICE.

GEORGE D. DOUGHTY, OF POST, TEXAS.

CROSS-WORD-PUZZLE GAME.

Application filed March 6, 1925. Serial No. 13,601.

To all whom it may concern:

Be it known that I, GEORGE D. DOUGHTY, a citizen of the United States, residing at Post, in the county of Garza and State of Texas, have invented new and useful Improvements in Cross-Word-Puzzle Games, of which the following is a specification.

This invention relates to games or game boards, and the primary object of the same is to provide an entertaining device of the class specified which is self-contained, simple in operation and wherein skill and chance are fairly combined to produce different cross words in accordance with the preparation of the playing field and playing pieces of the game.

A further object of the invention is to provide a cross word puzzle or game wherein the several components are so assembled that they will always be retained in associated relation and ready for operation by skillful manipulation.

With these and other objects and advantages in view, the invention consists in the construction and arrangement of the several parts which will be more fully hereinafter described and claimed.

In the drawing:

Fig. 1 is a plan view of a game embodying the features of the present invention.

Fig. 2 is a section on the line 2—2, Fig. 1, showing the playing pieces out of the sockets therefor.

Fig. 3 is a section on the line 3—3, Fig. 1, showing the playing pieces in the sockets therefor.

The improved game comprises a box or enclosure having a bottom 5, to which are suitably secured angularly disposed sides 40 and ends 6, in which a transparent plate 7 of glass or other material is fitted, as clearly shown by Fig. 2. The dimensions of the box or enclosure may be varied and the material used in the construction of the same 45 may be wood, metal, composition or any substance adapted for the purpose. In the upper side of the bottom 5 a plurality of sockets 8 and 9 are formed and of circular contour, the sockets 8 centrally intersecting the sockets 9, to produce a cross word figure when the puzzle is properly worked or solved. The sockets 8 and 9 are variously colored and have therein letters 10 disposed in the centers thereof. In addition to the 50 sockets 8 and 9 at what may be termed the bottom of the puzzle there is an enlarged 55

socket 11 of suitable color having imprinted or otherwise applied therein the words "Puzzle game", as at 12. Freely movable over the upper surface of the bottom 5 are a series of playing pieces 13 of disk form having letters 14 applied to the centers thereof and colored similarly to the sockets into which the said playing pieces or disks are adapted to be moved. A playing piece 15 with the words "Puzzle game", as at 16, thereon is also provided for movement into the socket 11, this playing piece 15 being colored similarly to the said latter socket. All of the playing pieces are similarly colored and lettered on both sides, so that in the event the same by any means may become overturned, they will be in condition for operation or for solving the puzzle in accordance with the features of the invention. 75 The playing pieces or disks 13 are slightly smaller in diameter than the diameter of the sockets 9, and likewise, the playing piece 15 is smaller than the socket 11 so that these respective playing pieces may be readily 80 disposed in the sockets.

In the present form of improved game the playing pieces or disks 13 are equal in number to the sockets 9 therefor and are lettered to spell the words "Cross" and "Word", the pieces when arranged to spell the word "Cross" extending transversely in one direction over the playing field or bottom 5, and the remaining pieces which are arranged to spell "Word" centrally 90 intersect the playing pieces spelling the word "Cross" at right angles. The puzzle is completed when the playing pieces 13 are disposed in the proper sockets therefor by the disposition of the playing piece 15 in 95 the socket 11, and when all of the playing pieces are in their respective sockets, the solved puzzle will present the words "Cross word puzzle game." It is obvious that the particular letters on the playing pieces and in the sockets may be modified or changed, and furthermore, the sockets and playing pieces may be increased in number to spell various words, the essential features of the invention residing in the corresponding 100 coloring and lettering of the playing pieces and sockets and the duplication of similar letters and colors on opposite sides of the said playing pieces or disks.

In operating the puzzle the player holds 110 the same in his hands and manipulates the entire enclosure by tilting or vibrating the

same in different directions in order to dispose the proper playing piece or disk in the socket corresponding thereto.

The improved puzzle game may be produced at a small expense and sold at a minimum cost, and will serve as an effective medium of entertainment and diversion.

What is claimed as new is:

1. A cross word puzzle game of the class specified comprising a bottom serving as a playing field and formed with a series of sockets differently colored and provided with characters therein, and a plurality of playing pieces of disk form colored similarly to the sockets and bearing corresponding characters thereon.

2. A cross word puzzle of the class specified comprising an enclosure having a bottom and a transparent top, the bottom being formed with a plurality of regularly arranged crossed sockets differently colored and having letters therein, and a plurality of

playing pieces shiftable to enter the sockets and colored similarly to the latter and also bearing corresponding letters to form a cross word when the playing pieces are properly disposed in the sockets.

3. A cross word puzzle of the class specified comprising an enclosure having a bottom and a transparent top, the bottom being formed with a plurality of regularly arranged crossed sockets differently colored and having letters therein, and a plurality of playing pieces shiftable to enter the sockets and colored similarly to the latter and also bearing corresponding letters to form a cross word when the playing pieces are properly disposed in the sockets, the playing pieces each being similarly colored on both sides and also bearing the same letter character on each side.

In testimony whereof I have hereunto set my hand.

GEORGE D. DOUGHTY.
